UNITED STATES PATENT OFFICE.

DAVID O. BRANT, OF OWENSMOUTH, CALIFORNIA.

DESIGN FOR A BUTTERMILK-CROCK.

57,580.

Specification for Design.

Patented Apr. 26, 1921.

Application filed June 18, 1919. Serial No. 305,185. Term of patent 7 years.

To all whom it may concern:

Be it known that I, DAVID O. BRANT, a citizen of the United States, residing at Owensmouth, in the county of Los Angeles and State of California, have invented a new, original, and ornamental Design for a Buttermilk-Crock, of which the following is a specification, reference being had to the accompanying drawing, forming part thereof.

In the drawing,

The figure is a perspective view showing my new design.

I claim:

The ornamental design for a buttermilk crock as shown.

DAVID O. BRANT.
